UNITED STATES PATENT OFFICE

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY

PRINTING MECHANISM FOR TABULATING MACHINES

Application filed June 20, 1928. Serial No. 286,840.

This invention relates to tabulating machines and more particularly to improvements in the printing mechanisms therefor.

Tabulating machines, as presently developed, are provided with printing mechanisms whereby numerals represented by index point perforations may be indicated by printing upon a record strip, and, in addition thereto, such printing mechanisms are also employed to represent the result of some computation, such as a total of a series of items. It frequently happens that it is desirable to identify the printed items or computations by printed words, abbreviations or the like, and in some instances this can readily be accomplished by substituting letter type for the numeral bearing type so that the index points will represent alphabetical or other characters. Due to the limitations in the number of index points in a card column, which is usually ten, a limited number of characters may be printed detracting from the usefulness of such an expedient.

It is then the main object of the present invention to extend the usefulness of such printing mechanisms whereby they may be called up when occasion requires to print either numerals, or substantially all of the alphabetical characters and under control of a single card column.

It is a further object to provide an improved mechanism designed to be controlled by a single card column which may print either alphabetical or numeral characters arranged in groups, which characters are far in excess of the number of index points in a card column.

It is a further object of the invention to devise an improved means whereby characters in certain groups may be selected by perforations in a particular field of the card.

It is a further object of the present invention to devise means whereby group selection and type selection occur during successive card feeding cycles and by separate analyzing means this delayed action permitting one set of brushes to control group selection during one card cycle and another set of brushes to select a desired type of the group during the next card cycle.

It is still a further object of the present invention to provide a mechanism employing a card having index points, each index point representing a numeral or a plurality of letters of the alphabet whereby such index points will select numerals or letters of the alphabet for printing, or by means of an additional index point may be given a differential alphabetical meaning.

In carrying out the present invention, the preferred means comprises a type carrying member provided with a plurality of groups of type, one group for example, being numeral type, the second, letters of the alphabet and the last, if so desired, other letters of the alphabet. The numeral group of type are normally presented to the printing point so that as the usual card perforations register with the analyzing brushes the type will be differentially selected. If a group selecting perforation should register with an upper or controlling brush the corresponding group of alphabetical characters will be selected prior to the differential selection of the type as controlled by the usual index point perforations. In this manner the card controlling columns may differentially control a number of type to make up, for example, either a number, word, or abbreviation.

These and other incidental objects which will be pointed out hereinafter will be clear from the following detailed description, in which;

Fig. 1 is a transverse sectional view through the printing mechanism illustrating a single embodiment of the invention;

Fig. 2 is a view similar to Fig. 1 illustrating the position of the parts for differentially selecting a type of the upper or alphabet group of type;

Fig. 3 is a view similar to Figs. 1 and 2 illustrating the position of the parts for differentially selecting a type of the lower or second group of alphabet type;

Fig. 4 is a circuit diagram of the machine to which the present improvements are applied;

Fig. 5 is a fragmentary representation of a part of a regular Hollerith card illustrated as

punched for selecting either numerals or letters by means of the present invention.

Referring to Fig. 1, drive shaft 25 driven by the tabulating motor T. M. (Fig. 4) carries a box cam 27 the race of which reciprocates a bell crank lever 28 one end of which is attached by a link 29 to a reciprocating cross head 30. A pair of levers 28 is provided to carry the cross head, the latter carrying a series of clutch pawls 31 adapted to engage with angular notches 32 formed in slidably mounted plates 33, one being provided for each printing order.

When lever 28 is actuated, the engagement of pawl 31 with notch 32 will cause the movement of plate 33 the latter then initially rising upwardly to a differentially stopped position. Plate 33 may rise until arrested by a pawl 34 operated by its associated magnet 35 and engaging in one of a series of notches 36 in the side edge of plate 33.

The spacing of notches 36 corresponds with the spacing of type bars 37 constituting, for example, numeral type bars of group A. It will be clear that as plate 33 rises differentially a rack portion 38 thereof will roll a pinion 39 counterclockwise over the rack teeth 41 of an impositively held plate 42. Pinion 39 is pivotally carried by the lower end of a slidably mounted plate 43 which carries at its upper end the set of numeral type 37 constituting group A. The movement of plate 43 is, therefore, synchronous with the differential movement of plate 33 bringing the desired type bar 37 in correspondence with a printing platen 44. The movement of plate 33 is also synchronous with the movement of perforated cards 45 (Fig. 5) through the machine so that when a perforation is encountered by a brush in the tabulator, the corresponding magnet 35 is energized, as will be hereinafter set forth, and the plates 33 and 43 are stopped at a point in their upward travel which brings the type corresponding to such perforation into the printing position and holds it there until after printing.

The plate 33 may be stopped prior to the time that the cross head 30 completes its upward movement in which case pawl 31 merely rides out of engagement with the related notch 32 permitting an upward independent movement of the cross head 30. As the cross head is moved reversely downwardly the pawl 31 will re-enter the notch 32 to positively restore the plate 33 to its normal position.

Any suitable means may be provided for impelling the selected type against the platen 44 to perform the printing function, and may constitute hammers 46 each of which impels an associated plunger 47 against the selected type. The hammers are adapted to be struck by a bail 48 having suitable connections to the operating parts of the machine. Since the hammer details form no part of the present invention they are not shown or described

in detail herein and for details of a preferred construction, reference may be had to the application of C. D. Lake, Serial No. 541,347, filed March 6, 1922.

In the manner just described any of the numerals may be selected for printing, the particular one selected depending upon the position of the index point in the card column. It is desirable, at times, to print letters to form words, abbreviations or the like and to this end plate 43 carries two other sets of alphabet type, the alphabet group B being arranged above the numeral group A while the alphabet group C is arranged below the numeral group A. The group of type B are selected for printing by an index point in the "R" position (see Fig. 5) while the group of type C are selected for printing by an index point in the "X" position. The type in the particular group selected are selected for printing by the usual index points in the card column.

The selection of the groups of type B and C in the present instance is controlled by the positioning of the slidably mounted plate 42 hereinbefore mentioned. It will be clear that if plate 42 is moved downwardly from the position shown in Fig. 1 to Fig. 2 the rack teeth 41 will cause pinion 39 to roll over rack teeth 38 in a counterclockwise direction drawing plate 43 downwardly to present the type of group B to the printing platen. Plate 42 is impositively held in its normal position by a plunger 49 engaging a notch 50 but when the plate 42 is moved to the position shown in Fig. 2 the plunger 49 will engage a notch 51 in the side edge of the plate. The extent that pinion 39 will roll over rack teeth 38 depends upon the upward differential arrested movement of plate 33, as hereinbefore described, so that by a composite opposite movement of plates 42 and 33 plate 43 may be adjusted to any intermediate position to select any type for printing. From Fig. 1 it will be observed that an equal and opposite movement of plates 33 and 42 during the time that the perforations are being analyzed will result in no movement of bar 43 but when a perforation in a card column causes the energization of a magnet 35 the pawl 34 engaging one of the notches 36 (Fig. 2) will stop the upward movement of plate 33. Plate 42 continues, however, to its lowermost position rolling pinion 39 counterclockwise over rack teeth 38 thus drawing plate 43 downwardly to select the third type from the top for printing. In a similar manner other type of group B may be selected for operation.

The preferred means employed to position plate 42 downwardly to select the alphabet type of group B comprises a cam slide 53 the lower cam surface of which coacts with a stud 54' carried by plate 42 so that as slide 53 moves to the left its coaction with stud 130

54' will cause plate 42 to be cammed downwardly to the position shown in Fig. 2. Slide 53 is provided with rack teeth 54 normally out of engagement but adapted to engage the teeth of a mutilated gear 55 which carries a clutch pawl 56 associated with a notch 58 formed in a constantly rotating shaft 59 driven by shaft 25 through a train of gears 26. Pawl 56 is normally held out of engagement with notch 58 by a latch pawl 60 which is actuated to non-latching position by a call rod 61 when a magnet 62 is energized.

As will be hereinafter explained magnet 62 is energized whenever a perforation appears in the "R" position and is energized prior to the time that the usual type selecting index points are analyzed. The engagement of pawl 56 with notch 58 results in subsequently driving slide 53 to the left by the gear 55 and against the tension of a restoring spring 63. As slide 53 reaches the position shown in Fig. 2, a straight edge or dwell 64 coacts with stud 54' during which time printing from the selected type is effected. At the termination of the movement of slide 53 to the left and after the printing operation pawl 56 (Fig. 2) strikes the end of restored latching pawl 60 resulting in the disengagement of pawl 56 with notch 58. Spring 63 restores the slide 53 to its normal position (Fig. 1) and independent of gear 55 since the teeth thereof clear the rack teeth 54 at the termination of the movement of slide 53.

Restoration of the slide 42 to its normal position to cause the numeral type of group A to again be normally selected is effected by a cam 65 (Fig. 2) attached to a constantly rotating shaft 66 since shaft 59 (Fig. 1) carries a gear 67 (Fig. 1) meshing with a similar gear 68 attached to the shaft 66. The profile of cam 65 coacts with a roller 69 (Fig. 2) carried by a lever 70, a pair being provided to support a cross rod 71 adapted to engage under projections 72 of the plates 42 to restore them to their upward normal position when said levers 70 are rocked by the cam 65. This restoring action occurs, of course, after the printing operations again positioning the type to normal position for selection in accordance with perforations of a successively fed record card.

A similar device is provided for selecting the type bars constituting the lowermost or group "C", which are also preferably alphabetical character bearing type. The C group of type are selected by an index point appearing in the so-called "X" position, which is the eleventh index point position on the card. The desired type in group C selected for printing is controlled in accordance with the usual index points appearing in the same column as the "X" index point.

A slide 73 coacting with stud 54' is provided for the purpose of elevating plate 42

to select group C type for operation, since it will be apparent that as plate 42 rises the rack teeth 41 will cause pinion 39 to roll clockwise over the rack teeth 38 to elevate plate 43 bringing the type of group C in correspondence with the printing platen 44, (see Fig. 3). This position of plate 43 is impositively held by the pin 49 coacting with a notch 74 in plate 42. The supplemental upward differential movement of plate 43 is controlled in the usual manner, that is, by the differential time energization of magnet 35 permitting pawl 34 to engage one of the notches 36 as plate 33 is elevated by bell crank lever 28. If plate 33 is arrested, the continued upward movement of plate 42 by the movement of slide 73 to the left will finally adjust plate 43 to select the desired type of group C for printing.

For the purpose of actuating plate 73 there is provided a mutilated gear 75 (Fig. 1) whose teeth are adapted to subsequently mesh with rack teeth 76 of slide 73. The mutilated gear carries the usual clutch pawl 77 adapted to engage a notch 78 in the constantly rotated shaft 66, the effective action of the clutch pawl being established when a latching pawl 79 is operated by the energization of magnet 80. Magnet 80 is energized when an index point appears in the "X" position. Slide 73 is restored to normal by the usual spring 81 while a cam 82 (Fig. 2) attached to shaft 59 rocks a pair of levers 83 to restore each plate 42 to its central normal position. The levers 83 carry a cross rod 84 which is positioned over the projections 72 to depress the plates 42 to normal. Restoration of the parts brings them to the position illustrated in Fig. 1 where the numeral type of group A may be normally selected for printing.

The construction and operation of the commutator mechanism for selectively controlling the energization of magnets 62 and 80 will be explained in connection with Fig. 4 of the drawings. The circuit diagram illustrated in this figure is similar to that disclosed in the co-pending application of G. F. Daly and R. E. Page, Serial No. 6,980, filed Feb. 5, 1925, the circuits being altered to include the new mechanism to realize the present advantages.

A card column controlling numeral printing does not contain the perforations X or R, and has only the usual index point perforation for differentially selecting a particular numeral type bar of the group A. These perforations are sensed by the lower brushes 85. The machine circuits are, as usual, energized from a source of energy indicated at 86 connected to line wires 88 and 89 by a double pole switch 87. As the record cards are fed through they are first presented to upper brushes 90 which senses card perforations at the X and R positions whereupon the card is fed during a subsequent card cycle to lower

brushes 85. These perforations close the counter magnet circuits traced as follows for one column, from the left side of the line 88, wire 91, contacts 92, counter magnet 93, brush 85, common bar 94, wire 95 to the right side of contacts T-2, T-3, and when the first card is being listed through contacts T-4, T-5, by wire 96 to binder post 11.

If a tabulating operation is being performed on a card other than the first group 10 the current instead of passing through T-4 and T-5 will pass through T-2, and T-3, wire 97, brush 98, segments 99, through commutator 100, brush 101, wire 96 to binder post 11.

15 After the machine has operated a certain amount contacts T-1 close, extending the circuit just described from binder post 11 through upper and lower card lever contacts 102 and 103, closed contacts T-1, binder post 9, closed contacts P-3 to the other side of the line.

20 The energization of counter magnet 93 sets up a supplementary circuit as follows: from the left side of the line 88, contacts 104, printer magnet 35, common bar 105, wire 106 to non-list switch 634 closed when listing is desired. When this switch is closed, during the first card cycle, and with the commutator circuit 101, 100 and brush 107 closed during the same card cycle, current would be supplied from binder post 11 to the common bar 105 through wire 106, contacts LP-1 now closed and through switch 634. In this way printer 25 call magnets 35 are provided with a return path for the current which, as will be understood, is a secondary circuit which has been completed by the energization of the counter magnets from the brushes and the subsequent 30 closing of contacts 104.

35 It will be understood that if no other perforations appear in a card column aside from the usual perforation in one of the ten designated points the numeral type in group A will be controlled differentially the particular type selected depending upon the differential time that printing magnet 35 is energized.

40 The upper brushes 90 which search the record cards for perforations at the X or R positions are energized through cam contacts 110 which close during the feeding of cards and open between successive card feeding cycles. Brushes 90 are, of course, electrically connected in some suitable manner to sockets 111 connecting the pairs of magnets 62, 45 80, and in the present instance this connection is exemplified by the jumper connections 112 thus electrically connecting a brush 90 and one of a pair of magnets 62 or 80, depending upon the perforation presented to the upper analyzing brush.

45 The commutator arrangement preferably provided for selectively controlling the energization of magnets 62 or 80 comprises a

cylindrical body of insulating material 113 rotating synchronously with the card feeding mechanism so that as an X perforation reaches a brush 90 a metal point 114 contacting with a brush 115 will cause the energization of magnet 62. But when a perforation at the "R" position is presented to a brush 90 another point 116 will simultaneously contact a brush 117 to cause the energization of magnet 80. The points 114 and 116 are electrically connected to a metal ring 118 against which a brush 119 bears. By either of the spots 114 or 116 the circuit extends from the magnets 62 or 80, through ring 118, brush 119, wire 120 to the usual cam contacts 121 to the other side of the line 89.

50 If the group controlling perforation should be at the 12th or R position magnet 62 will be energized and the energization of the magnet occurs when point 114 reaches brush 115 during the first card feeding cycle. This results in the subsequent engagement of pawl 56 (Fig. 1) with the notch 58 of the driving shaft 59 so that substantially at the time the analyzing brushes 85 search the usual index 55 points during the second card feeding cycle the teeth of gear 55 will engage the teeth 54 of slide 53 thereby actuating slide 53 to depress plate 42 during the same time that lever 28 is elevating plate 33. The latter will be arrested differentially when a particular magnet 35 is energized in accordance with the second or type selecting perforation. As the dwell 64 of slide 53 coacts with the stud 54' printing will be effected from the selected type of group B after which slide 53 is immediately restored. During the last part 60 of the second card feeding cycle cam 65 (Fig. 2) rocks lever 70 and through the medium of rod 71 plate 42 is restored to normal.

65 It will also be observed that since magnet 62 is momentarily energized to cause the clutching action between notch 58 and pawl 56 that a flat spring 122 (Fig. 1) is provided to restore latching pawl 60 to normal prior to the completion of the card feeding cycle in which the tripping action occurs. Thus the magnet 62 is held in readiness to control type group selection during the next card 70 feeding cycle.

75 The action of the parts for selecting the type of group C is similar to that described heretofore with the exception that a perforation at the X or 11th position will cause magnet 80 to be energized rendering the upper or "R" clutch operative. Thus when slide 73 is actuated the type carrying plate 43 will be elevated to select a particular type of group C for printing.

80 A relatively important phase of the invention is that the particular means provided for controlling group selection is active during a different card cycle than that in which type selection occurs. This permits the upper brushes to be used for performing the 85

function of group selection while during the subsequent card cycle the type to be selected may be controlled by the lower brushes. It will also be observed that a minimum movement of the type carrying plate is required to select the group of type not normally presented to the printing platen.

5 While there has been shown and described and pointed out the fundamental novel features of the invention as applied to a single modification it will be understood that various omissions and substitutions and changes in the form and details of the device illustrated and in its operation may be made by 10 those skilled in the art without departing from the spirit of the invention. It is the intention, therefore, to be limited only as indicated by the scope of the following claims:

10 1. In an accounting machine comprising in combination with a movable printing bar carrying a plurality of groups of type common to a card column, means whereby index points in a certain field of a controlling card controls the selection of a particular type in a group and means whereby other index points in another card field preliminarily controls the selection of the groups of type.

20 2. In an accounting machine comprising in combination with a movable printing bar carrying a plurality of groups of type common to a card column, controlling means whereby index points in a certain card field controls the selection of a particular group of type, and additional controlling means whereby other index points in another card field controls the selection of a particular type in a group, both said controlling means operating in alternating sequence.

30 3. In an accounting machine comprising in combination with a movable printing bar carrying a plurality of groups of type common to a card column, controlling means whereby index points in a certain card field controls the selection of a particular group of type, and additional controlling means whereby other index points in another card field controls the selection of a particular type in a group, said group selecting means operating prior to said type selecting means.

40 4. In an accounting machine comprising in combination a movable bar provided with a plurality of groups of type, a reciprocating member adapted to present a preselected group of type to a printing point and card controlled means for subsequently selecting a particular type of the pre-selected group.

50 5. In an accounting machine comprising in combination groups of type common to a card column and each type having a common printing point, card analyzing means for selecting a group of type, and additional card analyzing means subsequently effective for selecting a type of the pre-selected group.

60 6. In an accounting machine comprising

in combination groups of type common to a column of a controlling record card and each type having a common printing point, card analyzing means for selecting a group of type, additional card analyzing means for 70 selecting a type of the pre-selected group, said analyzing means being operable in alternating sequence.

7. In a tabulating machine comprising in combination with a movable bar carrying a 75 plurality of groups of type, of analyzing brushes for analyzing a certain field of a record card in motion to control the selection of a group of type and an additional set of brushes for analyzing another card 80 field of the same record card while in motion to control the selection of a type of the selected group.

8. In a tabulating machine comprising in combination with a bar carrying a plurality 85 of groups of type, of analyzing brushes for analyzing a certain field of a record card to control the selection of a group of type and an additional set of brushes for analyzing another card field to control the selection of 90 a type of the selected group, said analyzing means being operable in alternating sequence.

9. In a tabulating machine comprising in combination with a bar carrying a plurality of groups of type the aggregate type being in excess 95 of the number of index points in a column of a controlling record card, and electrically-actuated analyzing means for controlling the moving of said bar to preselect during one cycle a group of type and to select during 100 a later cycle type of the selected group in accordance with the index points of the card.

10. In a tabulating machine comprising in combination with a reciprocable member having a normal starting position and carrying a plurality of groups of type, a printing platen cooperating therewith, and record card controlled means operable in successive machine cycles whereby said member is differentially adjusted from a normal starting 110 position to select a particular type of a group as the preselected group of type advances toward the printing platen.

11. In a tabulating machine comprising in combination with a plurality of groups of 115 type common to a column of a record card and each type having a common printing point, analyzing brushes operable during a card feeding cycle for controlling group selection, and additional analyzing brushes operable during a subsequent card feeding cycle for controlling the selection of a type of a selected group.

12. In an accounting machine comprising in combination, with a printing bar carrying a plurality of groups of type common to a card column, means whereby index points in one card field are analyzed during one card cycle to control the selection of a group of type, and means whereby index points in an- 130

other card field are analyzed a card cycle later to control the selection of a type in the pre-selected group.

13. In an accounting machine comprising in combination, a bar provided with a plurality of groups of alphabetical type characters and a group of numeral type the latter being normally presented to the printing point, card controlled means including index points analyzed during one card cycle for selecting a group of alphabetical type, and additional index points in another card field analyzed during a subsequent card cycle for selecting either a type of a preselected group of alphabet type or a type of the numeral group.

14. In a tabulating machine comprising in combination with movable member carrying a plurality of groups of printing type, record card controlling means effective during one card cycle whereby said member is adjusted to select a group of type, record card controlling means effective during a subsequent card cycle for selecting a type in the selected group, and means for positively restoring said member subsequent to type selecting operations.

15. In a tabulating machine comprising in combination with a member carrying a plurality of groups of printing type, record card controlled means for adjusting said member to bring a preselected group of type to the printing point, additional record card controlled means for supplementally and differentially adjusting said member while said selected group of type is presented to the printing point, and means for positively restoring said printing member subsequent to differential type selecting operations.

16. In a tabulating machine comprising in combination with a movable member carrying a plurality of alphabetical printing type divided into groups, means whereby a particular field of a card analyzed during one card cycle controls the selection of type in either group, and additional means controlled by another field of the card analyzed during a preceding card cycle for preselecting a group of type.

17. In a tabulating machine comprising in combination with a member carrying a plurality of groups of type, a printing platen cooperating therewith, and means controlled by the fields of a record card analyzed during successive machine cycles for differentially adjusting said member to select a type of a preselected group.

18. In a record controlled machine, in combination, a reciprocable member carrying a plurality of groups of type, record controlled actuating means for shifting said member in a certain plane to select a group of type, and separate actuating means controlled from a separate field of a card for

shifting said member in the same plane to select a type of the selected group.

19. In a tabulating machine comprising in combination, a member carrying a plurality of groups of type each group being in the normal printing line, actuating means for selecting a group of type, separate actuating means for selecting a type of the selected group, and means controlled by separate fields of a record card for controlling the operation of the group and type selecting and actuating means.

20. In a tabulating machine, comprising in combination, a member carrying a plurality of groups of type, means for actuating said member to select a group of type, means for actuating said member to select a type of a selected group, and means controlled by separate fields of a record card analyzed during successive operations for controlling the separate actuating means.

21. In a machine of the class described, in combination, a platen, a member carrying three groups of type in the same plane, one group being normally positioned to the platen, and separate record controlled actuating means for adjusting said member in the plane of the type to present either of the remaining groups of type to said platen.

22. In a machine of the class described, in combination, a platen, a member carrying a plurality of groups of type in the same plane, and record controlled actuating means for shifting said member oppositely but in the same plane to present either group of type to the platen.

23. In a machine of the class described, in combination, a platen, a member carrying a plurality of groups of type in the same plane, the intermediate group being normally presented to the platen, and record controlled means for shifting said member oppositely from the intermediate group but in the same plane to present either of the two remaining groups to the platen.

24. A tabulating machine comprising in combination with means for feeding record cards having separate card fields representing groups of type and individual type of the groups, of means whereby said separate card fields are analyzed during different card feeding cycles, and electrically controlled means whereby group and type selections occur contemporaneously.

25. In an accounting machine, in combination, a bar provided with a plurality of groups of alphabet type and a group of numeral type, means controlled by cards in motion for selecting the numeral type, and other card controlled means for selecting the groups of alphabet type, the alphabet type in the selected group being selected by the first named card controlled means.

In testimony whereof I hereto affix my signature.

JAMES W. BRYCE.
